UNITED STATES PATENT OFFICE

2,084,192

INCANDESCENT LAMP AND SIMILAR DEVICE

Paul O. Cartun, Cleveland Heights, Ohio, assignor
to General Electric Company, a corporation of
New York

Application May 3, 1933, Serial No. 669,189

4 Claims. (Cl. 176—32)

My invention relates to electric incandescent lamps and similar devices comprising an electric energy translation element, such as a filament, enclosed or sealed in a bulb or envelope. Heretofore, the practice has been to provide such a device with a separate "base" united to its hermetically sealed glass bulb or envelope by cement or other means; this bulb supporting the internal "mount" of the lamp or the like, comprising the translation element and its supporting structure inside the bulb. Typically, the unitary base structure not only serves as a means for mounting the lamp, but also includes terminals or contacts connected to conductors leading into the bulb through the glass to the translation element inside.

According to my invention, as distinguished from the practice above mentioned, the bulb neck or end is sealed to an end member on which the internal mount of the lamp is mounted independently of the attachment of the bulb. This member or disk is provided with engagement means for mounting the lamp: e. g., the member may form part of a base or terminal device more or less resembling those heretofore used; or such a base may be attached to the member, or united directly thereto; or the disk member itself may be engaged by the securing means of the lamp support. In this way, the member or disk becomes an integral part of the lamp,—even, indeed, a part of the enclosing envelope itself. The internal mount of the lamp is supported directly by the member or disk, instead of through the medium of the bulb, as heretofore. The current leads need no longer pass through the glass envelope; the usual separate basing operation can be eliminated; and it becomes much easier to locate the translation element accurately and uniformly with reference to the engagement means of the base. This is specially advantageous for lamps used with light projection devices such as reflectors, projectors with lenses, etc.; since by accurately locating their sockets or other lamp holding means according to definite standards, standard lamps constructed according to my invention can be efficiently used in them without any necessity or provision for focusing adjustments. Moreover, the lamp is much simpler and stronger, and less expensive to make. Various other features and advantages of the invention will appear from the following description of species thereof, and from the drawing.

In the drawing, Fig. 1 is a perspective view of an illustrative lamp embodying my invention; Fig. 2 is a vertical section through a portion thereof,

illustrating a form of construction representing one species of my invention; Fig. 3 is a similar section illustrating another species; Fig. 4 is a perspective view of another species of lamp; Fig. 5 is a perspective view partly sectioned of a mounting for the lamp shown in Fig. 4; Fig. 6 is a view similar to Fig. 4 of still another species of lamp; and Fig. 7 is a view similar to Fig. 5 of another species of mounting.

The device shown in Fig. 1 is an incandescent electric lamp having as its electric energy translation element a filament 10 within a glass bulb 11, connected between wires 12 and 13 attached to its ends, and additionally supported, at intermediate points, by wires 14 whose ends are fused into a glass bead 15, itself fused to the wire 13. To increase the rigidity of the supporting structure, a brace wire 16 fused into the bead 15 at one end is welded at its other end to the wire 12. In the present instance, the wires 12, 13 not only support the filament 10, but also serve as its current leads. The "mount", comprising the filament 10 and its supporting means just described, is attached directly to a sheet metal diaphragm or disk 17 forming part of (or attached to) a base 18, and extending across the interior of the base shell 19 at its upper end. The base 18, shown of an Edison or screw type, has a screw-threaded shell 19, serving as one base contact, and has another base contact 20 exposed at its lower end, but insulated from the shell 19. The lower end or neck of the bulb 11 is sealed directly to the diaphragm or disk 17. As shown, the base 18 proper (exclusive of the disk 17) may be the standard Edison base now in general use, consisting of brass screw shell 19 with apertured brass center contact 20 held in place by glass 21 fixed in the inward flanged bottom opening of the shell. The upper end of the shell 19 engages around an outstanding peripheral lip 22 on the circular disk 17, and is attached thereto (by welding).

As a matter of manufacturing practice, the disk 17 may be separate from the base 18 proper when the bulb 11 is sealed to the disk, and the base shell 19 may afterward be affixed around the disk. By doing this with the upper edge of the shell 19 flush with that of the disk lip 22, it is easy to locate the base 18 accurately with reference to the filament 10.

The bulb 11 is preferably made of soft glass, and the diaphragm or disk 17 of a metal or alloy (such as an iron alloy containing about 25% of chromium) which has the same thermal coefficient of expansion as glass, and to which glass

55

is readily sealable. In the sealing operation, the end of the bulb 11 may be pressed while hot against the heated disk 17 and thereby also sealed to the inner surface of the lip 22. The lip 22 affords additional adhesion area, but is preferably of such small height (e. g., of a magnitude comparable to the thickness of the glass) that it could not shade or cut off useful light from the filament 10.

10 In mounting the filament supporting structure on the disk 17, the wire 12 may be attached by welding it to the disk, and the wire 13 may extend through an opening 23 in the disk, and be embedded and secured in a fused body of glass 24 which closes and seals the opening. The seal 24 may be formed from the residue of a glass exhaust tube (not shown) sealed to the disk at the opening 23, and sealed off (after use) around the wire 13. This may all be done before the base 18 15 proper is affixed to the disk 17. The portion of the wire 13 embedded in the glass 24 is preferably made of material similar to the disk 17, or such as heretofore used for incandescent lamp leads sealed in glass.

20 25 In the construction shown in Fig. 3, the base 25 includes a brass screw shell 19 like that of a standard Edison screw base, and the apertured diaphragm or disk 26 extends across its lower end, being attached (by welding) to the inturned 30 bottom shell flange. Accordingly, the shell 19 surrounds the end or neck of the bulb 11. The end of wire 13 is exposed beyond the seal 24 to serve as a center contact. The disk 26 is shown slightly smaller than the interior of the shell 19, 35 and without any peripheral lip. The shell 19 may be attached to the disk 26 after the latter has been sealed to the bulb 11 and the lamp exhausted and sealed at 24, as described above; or, if preferred, the disk 26 may first be attached (welded) 40 to the shell 19 so as to form part thereof, and this composite base shell may afterward be applied and sealed to the bulb neck, and the lamp subsequently exhausted and sealed at 24. Obviously, the shell 19 and disk 26 of Fig. 3 might be 45 made as one complete bottom shell of the material hereinbefore indicated for the disks 17 and 26.

The lamp shown in Fig. 4 comprises a glass bulb or envelope 21 abutting endwise and sealed against an apertured sheet metal disk 28 which 50 itself forms the terminal device or base of the lamp. This disk 28 has securing wings, ears, or blades 29 formed by integral extensions of the shell metal from the generally circular disk periphery, for engaging suitable mounting means. 55 The internal lamp mount is attached to the disk 28 as in Fig. 3; i. e., the wire 30 is welded to the disk, one of whose wings 29 serves as a base contact, and the wire 31 is secured and insulated in the fused glass tip or "spur" 32 sealing the disk 60 opening, and projects therefrom as a central bottom contact 33. The disk 28 may be of the iron-chromium alloy hereinbefore mentioned.

Fig. 5 shows a mounting device for the lamp of Fig. 4, comprising an insulative base plate 34 with 65 a central socket hole 35 for the base spur 32, spring contact clips 36 for receiving and gripping the disk wings 29, and a spring finger 37 for abutting against the center contact 33. Current supply conductors are connected to one (at least) of the clips 36 and to the finger 37. To mount the lamp in this device, its bottom spur 32 is inserted or pressed home in the hole 35 with the wings 29 intermediate the clips 36, and the lamp is then turned clockwise about the spur 32 as a pivot

sufficiently to force the wings 29 into the clips, which yield resiliently to receive and grip the wings. The wings or blades 29 underlock with the upper portions of the clips 36.

Fig. 6 shows a lamp similar to that of Fig. 4, 5 but with a larger iron-chromium sheet metal disk 40, having its integral peripheral wings or blades 41 retroverted under the disk 40 with clearance between sufficient to take the upper members of the clips 36 in Fig. 5; so that when the lamp is 10 mounted, the securing means and connections are all concealed under the disk.

Fig. 7 shows another mounting device, with (three) upstanding inward-shouldered spring contact clips 42 amongst which the disks 28 or 15 40 of Figs. 4 and 6 may be inserted and peripherally engaged. Otherwise, this device is like that of Fig. 5. With this Fig. 7 device, the wings 29 of Fig. 4 would be superfluous, and the wings 41 of Fig. 6 would act as mere spacers to augment 20 the effective thickness of the disk with reference to its edge engagement under the clip shoulders.

The iron chromium alloy (hereinbefore referred to) which I prefer is one marketed by the Allegheny Steel Company as "Allegheny 55," 25 of which the following is a typical percentage-by-weight analysis:

Iron	67.6 to 71.5
Chromium	26 to 30
Manganese	under 1
Nickel	do .6
Silicon	do .6
Carbon	do .25
Sulphur	do .025
Phosphorus	do .025

The structure shown in Figs. 4-7 is not claimed herein but is described and claimed in my divisional application Serial No. 116,583, filed December 18, 1936.

What I claim as new and desire to secure by Letters Patent of the United States, is,—

1. An electric device comprising a glass bulb or envelope having an opening therein, a base comprising a disk of metal having substantially the same coefficient of expansion as said glass bulb sealed by fusion directly to the edges of said bulb opening and forming with said bulb a hermetically sealed enclosure, said disk being provided with socket engagement means at its periphery, a filament in said bulb, a pair of leads secured one to each end of said filament, an end of one of said leads being attached to said disk and electrically connected through said disk to said socket engagement means, and the other lead extending through an aperture in said disk, said aperture being sealed by a body of insulating material surrounding said lead.

2. An incandescent electric lamp comprising a glass bulb or envelope having an opening therein, a disk of metal having substantially the same coefficient of expansion as said glass bulb sealed by fusion directly to the edges of said bulb opening and forming with said bulb a hermetically sealed enclosure, a base comprising a metal shell adapted to engage in a socket and secured at one end to said disk and carrying an end contact at its other end insulated from said shell, a filament in said bulb, a pair of leads secured one to each end of said filament, an end of one of said leads being attached to said disk and electrically connected through said disk to said shell, the other lead extending through an aperture in said disk and being electrically connected to said end contact, said aperture in said disk being sealed

by a body of insulating material surrounding said lead.

3. An incandescent electric lamp comprising a glass bulb or envelope having an opening at its end, a disk of metal having substantially the same coefficient of expansion as said glass bulb sealed by fusion directly to the edges of said bulb opening and forming with said bulb a hermetically sealed enclosure, a metal base shell adapted 10 to engage in a socket and surrounding the said end of said bulb and secured at one end to said disk, a filament in said bulb, a pair of leads secured one to each end of said filament, an end of one of said leads being attached to said disk 15 and electrically connected through said disk to

said shell, the other lead extending through an aperture in said disk and being exposed at the outer side thereof to serve as an end contact, said aperture in said disk being sealed by a body of insulating material surrounding said lead.

4. An electric device comprising a glass bulb having an opening therein, a base including a metal shell and a disk of metal readily sealable to glass attached to said shell, said disk being sealed directly to the edges of said bulb opening and forming with said bulb a hermetically sealed enclosure, and an energy translation element in said bulb with supporting means therefor attached to said disk independently of said bulb.
